UNITED STATES PATENT OFFICE.

GEORGE C. WILTHEW, OF MAHANOY CITY, PENNSYLVANIA.

MINING APPARATUS.

1,164,900.

Specification of Letters Patent. Patented Dec. 21, 1915.

Application filed July 22, 1913, Serial No. 780,550. Renewed August 28, 1915. Serial No. 47,891.

To all whom it may concern:

Be it known that I, GEORGE C. WILTHEW, a citizen of the United States, residing at Mahanoy City, in the county of Schuylkill and State of Pennsylvania, have invented new and useful Improvements in Mining Apparatus, of which the following is a specification.

This invention relates to mining apparatus, particularly designed for use in coal mining, the object of the invention being to provide a drilling apparatus which is light in weight, capable of being taken apart and easily transported and handled, and particularly designed for use in heavy pitch work in which drills of ordinary construction can not conveniently be employed.

A further object of the invention is to provide a drill which comprises a comparatively small number of parts, and in which the drill proper is provided with combined cutting teeth and threads, whereby the drill may be directly revolved and fed forward in its work.

The invention consists of the features of construction, combination and arrangement of parts herein fully described and claimed, reference being had to the accompanying drawings in which:—

Figure 1 is a side elevation of the device and illustrating its mode of use. Fig. 2 is a top plan view of the same. Fig. 3 is a vertical transverse section on the line 3—3 of Fig. 2. Figs. 4 and 5 are perspective views of the bracket and bearing member detached. Fig. 6 is a detail view of the bearing member showing the jaws thrown in open position. Fig. 7 is a detail view of a portion of the drill on an enlarged scale. Fig. 8 is a detail view of the anchor bar.

In carrying my invention into practice, I provide a drilling apparatus comprising a drill 1 terminating at its forward end in a drill point 2 and at its rear end in a shank 3. The drill is of the twisted type, and is formed with a continuous spiral surface 4 having continuous transverse threads 5. The shank 3 is adapted to fit within the socket 6 of any suitable type of driving brace or element 7. The drill is adapted to be supported in practice from the bank of coal which is being drilled by an anchor bar 8 having a pointed end 9 to enter a hole drilled in the bank, and provided near its opposite end with an opening 10. The open-

ing 10 is adapted to receive and engage a pin or projection 11 on a supporting bracket or yoke 12. The arms of this yoke are provided with openings 13 to receive trunnions 14 on a bearing member 15. This bearing member comprises upper and lower jaws 16 and 17 provided with complementary internally threaded semicircular central portions 18, providing a threaded socket 65 through which the drill extends and the threads of which are adapted to engage the threads of said drill.

As shown, the lower jaw 16 of the bearing member is provided with trunnions 14, and said jaw is formed at one end with an enlargement or knuckle 19 fitting between spaced ears 20 on the adjacent side of the jaw 17, said enlargement and ears being perforated for the passage of a pintle pin 21, whereby said jaws are pivotally connected for opening and closing movements. At its opposite side the jaw 16 is provided with a lug or projection 22 adapted to pass through an opening 23 in the adjacent side of the jaw 17, said projection 22 being apertured for the passage of a locking key 24, whereby the jaws may be held closed about the drill or released and opened to permit the bracket and bearing member to be disconnected from the drill. As the anchor bar is detachably connected with the bracket and the drill with the brace or driving element, it will be apparent that the parts of the appliance may be at any time conveniently disassembled to permit the apparatus to be conveniently transported from place to place or packed for storage or shipment. Furthermore, it will be seen that the device comprises a comparatively small number of parts, so that an apparatus which is light in weight, and is yet efficient in construction, may be provided for drilling on heavy pitch work and in places comparatively difficult of access where large and cumbersome drilling appliances of ordinary construction can not readily, if at all, be used.

In the operation of drilling a bank of coal, a small hole is first formed in the bank by means of a small drill operated by the brace or driving element. This drill is then removed, the anchor bar inserted in the opening thus formed, as shown in Fig. 1, the pin 11 of the supporting bracket 12 fitted in the opening 10, the drill 1 mounted in position 110 upon the bearing member and the brace 7 applied to the shank 3. The drill will then

be supported in position by the bar 8 and may be adjusted to work at any angle by the pivotal connection between the bearing member and bracket and operated by the brace 5 or driving connection 7. As the drill is rotated the bit thereof cuts into the bank and the threads engage the threads of the bearing member, whereby the drill is positively fed forward. When the bore is completed, 10 the apparatus may be removed in an obvious manner and transported in entirety or in a disassembled condition to another point for use, as will be readily understood.

From the foregoing description, taken in 15 connection with the drawings, the construction, mode of operation and advantages of my improved drilling apparatus will be readily understood, and it will be seen that simplicity is secured by providing the drill 20 with a combined cutting and threaded surface, enabling the operating parts coating therewith to be reduced to the minimum.

I claim:—

A drilling apparatus comprising a yoke having bearing openings in its side arms, a threaded bearing member having trunnions at its ends journaled in said bearing open-

ings, and provided at one of its ends with a knuckle and at its opposite end with a transversely disposed projecting lug, a second threaded bearing member provided at one end with spaced ears receiving said knuckle and pivotally connected thereto and provided at its opposite end with a slot for the reception and passage of said slotted lug, 35 the threaded surfaces of the bearing members being opposed and of semi-circular form to provide a circular passage, a wedge key engaging the slotted lug to hold said bearing members assembled, a drill extending through the passage formed by the bearing members and having a continuous spiral surface provided with threads to engage the thread surfaces of said bearing members, means for rotating said drill, a projection 40 from the cross portion of the yoke, and an anchor bar pivoted to said projection and provided with a pointed free end.

In testimony whereof I affix my signature in presence of two witnesses.

GEORGE C. WILTHEW.
